(57) **CLAIM**

The ornamental design for a toilet seat handle, as shown and described.

DESCRIPTION

FIG. 1 is An isometric underside view of the toilet seat handle which view shows my new design;

FIG. 2 is an upper isometric and left hand view thereof;

FIG. 3 is a top plan view thereof;

FIG. 4 is a rear elevational view thereof;

FIG. 5 is a bottom plan view thereof;

FIG. 6 is a front elevational view thereof;

FIG. 7 is an elevational view from the right side thereof; and,

FIG. 8 is an elevational view from the left side thereof.

FIGS. 2-8 are shown on an enlarged scale.
The broken lines are for illustrative purposes only and form no part of the claimed design.
